UNITED STATES PATENT OFFICE.

STANLEY S. COVERT, OF MONTCLAIR, NEW JERSEY.

CHIMNEY-FLUE REVERSER.

1,074,252.

Specification of Letters Patent. Patented Sept. 30, 1913.

Application filed April 18, 1912. Serial No. 691,666.

To all whom it may concern:

Be it known that I, STANLEY S. COVERT, a citizen of the United States, and resident of Montclair, in the county of Essex and State 5 of New Jersey, have invented certain new and useful Improvements in Chimney-Flue Reversers, of which the following is a specification.

In constructing chimneys it is frequently 10 found desirable to offset or reverse the position of one portion of a flue with respect to another portion, and in chimneys having linings, such as terra cotta and the like, of oblong rectangular cross section, the arrangement 15 of the flues is frequently such that the lining for one portion of a flue will be turned at right angles to the lining for an upper or lower portion of such flue.

The object of my invention is to provide 20 a chimney flue reverser of such construction as to be readily adapted to aid in reversing the relative arrangement of one portion of a chimney flue with respect to another portion thereof, and to properly fit between the 25 ends of flue linings which are at right angles to each other with respect to their greater length.

To this end my improved reverser comprises a hollow body or casing having upper 30 and lower oblong openings, the planes of the greater lengths of which openings are disposed at angles with respect to each other, whereby by fitting my improved reverser within a flue the position of the flue 35 or a portion thereof above the reverser may be reversed with respect to the position of the flue or a portion thereof below the reverser, the flue linings, when used, being correspondingly reversed, my reverser serving 40 in the nature of a liner for that portion of the flue in which the reverser is located.

My invention also comprises novel details of improvement that will be more fully hereinafter set forth and then pointed out 45 in the claims.

Reference is to be had to the accompanying drawings forming part hereof, wherein—

Figure 1 is a plan view of my improved 50 chimney flue reverser; Fig. 2 is a view looking at the under side of Fig. 1; Fig. 3 is a perspective view of the reverser; Fig. 4 is a perspective view similar to Fig. 3 inverted; Fig. 5 is a sectional view illustrating 55 my improved reverser in position in a chim-

ney flue; and Fig. 6 is a perspective view of a modified form of reverser.

Similar numerals and letters of reference indicate corresponding parts in the several views.

My improved chimney flue reverser, indicated generally at 1, comprises a hollow body or casing of suitable material, such as concrete, terra cotta or the like, having at opposite ends openings 1^a, that are shown as 60 oblong rectangles or geometrically oblong, disposed with the greater length of one opening at right angles to the greater length of the other opening. As shown, the longer edges 1^b of two opposed sides or walls are 65 opposed to the shorter edges 1^c of said sides or walls, and the shorter edges 1^d of two other opposed sides or walls (that are between the edges 1^b) are opposed to the longer edges 1^e of the last named sides or 70 walls (that are between the shorter edges 1^c). As shown in Figs. 1 to 5 the sides a, b, are at right angles to each other, the edge c being inclined between the edges 1^b, 1^c of side b; the edge d of side a inclines from the 75 edge 1^c to the edge 1^d of said side; the edge 1^f of the side f inclines from the edge 1^e to the edge 1^d of such side, and the side g inclines corresponding to the edges d, e, whereby marginal portions of the openings 80 1^a, 1^b, have a common right angle along the edge b', but as the planes of the greater lengths of said openings are shown at right angles to each other, each of said openings extends in its greatest length beyond the 85 plane of the corresponding side or edge of the width of the opposite opening, whereby a portion of one opening 1^a is offset with respect to a portion of the other opening 1^a. The sides a and b are thus substantially 90 similar in shape and dimensions, but inverted with respect to each other, and the sides f and g are also substantially similar to each other but inverted with respect to one another, whereby the effect stated of one opening 1^a extending in its greatest length beyond the plane of the corresponding side of the width of the other opening 1^a is 95 effected.

In Fig. 6 the arrangement of the reverser 100 is in general substantially similar to that before described in that the openings 1^a are at right angles to each other, but the upper opening 1^a overlies the lower opening 1^a symmetrically, that is to say, the extension 110

of the greater length of one opening on opposite sides of planes passing through the sides of the other opening 1^a is substantially equal, and vice versa. In such construction 5 the sides or walls of the reverser are shown in the form of trapezoids, whereby such trapezoidal sides or walls are of the same angles, and dimensions, but one such side or wall is reversed in position with respect to 10 two adjacent sides or walls.

The reverser is placed at a suitable position within, and at a desired relation to, the flue 2 of a chimney, and the flue is constructed, below and above the reverser, for a 15 desired distance, with its transverse dimensions or sections corresponding in position to the openings 1^a of the reverser; that is to say, the portion of the flue below the reverser will have its transverse length or 20 greater dimension parallel with the plane of the lower opening 1^a of the reverser, and its transverse length or greater dimension above the reverser parallel with the plane of the upper opening 1^a of the reverser, and thus 25 at right angles to the greater width of the portion of the flue below the reverser.

My improved reverser is particularly useful in connection with linings 3, 4, for the flue, which may be of terra cotta, concrete or 30 other material customarily used for such linings, which linings will be of cross sectional shape and dimensions substantially the same as the corresponding dimensions of the ends of the reverser. In Fig. 5 the lower 35 portion of the flue and the liner 3 are represented with the greater width of the flue and the greater length of lower opening 1^a running rearwardly, and the upper portion of the flue and liner 4 with the greater width 40 running transversely of the sheet, and it will be noted that in this case the flue portion and lining 4 are offset to one side of the vertical plane of wall 3^a of lining 3. This arrangement of the reverser enables one portion 45 of the flue and its lining to be offset with respect to another portion of the flue as well as to have the position of one portion of the greater width of the flue reversed with respect to another portion of the flue.

The lining 3 may be set in the chimney as 50 the latter is being built, the reverser 1 set upon lining 3 and the chimney continued upwardly along the reverser, and the lining 4 may be set upon the reverser and the chimney continued along lining 4.

It will be understood that as many reversers may be placed in a flue as desired, according to the required relation of the portions of the flue.

60 My improved reversers are adapted to be set in chimney flues where portions of such flues are to be offset or reversed with respect to one another, that is to say, where the greater width 65 of a flue is extended upwardly for a desired

distance, and then an upper portion of the flue is to be built with its greater width at right angles to the greater width of such lower portion of the flue. My improved reverser enables ready building of the flue 70 in such relations, and is particularly useful, where linings for the flue are used, in aiding the setting of the upper lining that is reversed with respect to the lower lining, the reverser forming a continuation or lining section between the reversed lining portions. 75

While the openings 1^a of my improved reverser are shown in oblong rectangular form to accord with corresponding oblong 80 rectangular linings, it will be understood that the openings 1^a of the reverser, while made oblong and substantially at right angles to one another in the direction of the planes of their greater lengths, may have 85 other cross sections, such as oblong-elliptical.

An advantage of my invention is that the dimensions of the reverser may be such that the cross sectional area of the interior 90 or flue portion of the reverser may be the same at all points of the reverser, thus enabling a flue, containing the reverser, to be constructed of equal capacity at all points.

Changes may be made in the details of 95 construction and arrangements set forth, within the scope of the appended claims, without departing from the spirit of my invention.

Having now described my invention what 100 I claim is:—

1. A device of the character described comprising a four-sided hollow block having two adjacent sides of similar angles and dimensions reversed in position with 105 respect to one another, and having two other adjacent sides of similar angles and dimensions reversed in position with respect to one another, said body having openings at its opposite ends of practically the 110 same dimensions, whereby said openings are angularly disposed as to their relative dimensions.

2. A device of the character described comprising a four-sided hollow block having two adjacent sides of similar angles and dimensions reversed in position with respect to one another, and having two other adjacent sides of similar angles and dimensions reversed in position with respect to 115 one another, said body having openings at its opposite ends, said openings each having greater length than breadth, the plane of the greater length of one opening being at an angle to the plane of the greater length of 120 the opening, said opening being on substantially parallel planes.

3. A device of the character described, comprising a hollow body having four sides, two adjacent sides being at right angles to 130

each other; the lower edge of one of said sides being longer than its upper edge, and the lower edge of the other of said sides being shorter than its upper edge, said body 5 having two other sides inclined with respect to the first named two sides, the lower edge of one of the second named sides being shorter than the upper edge of said side, and the lower edge of the other of said sides 10 being longer than the upper edge of said side, said body having openings at its opposite ends of practically the same dimensions.

4. A chimney flue provided with a reverser comprising a hollow body having openings at opposite ends that are of greater length than breadth, the plane of the greater length of one opening being at an angle to the plane of the greater length 15 of the other opening, the flue having greater transverse length than width, a portion of the flue having its greater transverse length at an angle to the length of another portion thereof, the reverser being interposed between such portions of the flue, and having the greater length of its respective openings extending in the direction of the corresponding portions of the flue.

5. A chimney flue provided with a reverser comprising a hollow body having openings at opposite ends that are of greater length than breadth, the plane of the greater length of one opening being at an angle to the plane of the greater length 20 of the other opening, the flue being provided with a lining above and below the reverser, the linings having greater cross-sectional length than breadth, the greater such length of one 25 lining coinciding with the greater length of one opening of the reverser, and the greater such length of another lining coinciding with the greater length of the other opening of the reverser, the greater such length of said linings being at an angle to each other.

reverser, the linings having greater cross sectional length than breadth, the greater such length of one lining coinciding with the greater length of one opening of the 40 reverser, and the greater such length of another lining coinciding with the greater length of the other opening of the reverser, the greater such length of said linings being at an angle to each other.

6. A chimney flue provided with a reverser comprising a hollow body having openings at opposite ends that are of greater length than breadth, the plane of the greater length of one opening being at an angle 45 to the plane of the greater length of the other opening, the flue being provided with a lining above and below the reverser, the linings having greater cross-sectional length than breadth, the greater such length of one 50 lining coinciding with the greater length of one opening of the reverser, and the greater such length of another lining coinciding with the greater length of the other opening of the reverser, the greater such length 55 of said linings being at an angle to each other and corresponding to the angles of the respective planes of said openings of the reverser.

Signed at New York city, in the county 60 of New York and State of New York this 16th day of April, A. D. 1912.

STANLEY S. COVERT.
